PETTI-BRA SLIP

Julia Read, New York, N. Y.

Application June 7, 1946, Serial No. 675,224

3 Claims. (Cl. 2—73)

1

This invention relates to garment construction and in particular to one applied to a combination slip and brassière.

The average woman must wear, under an outer dress or garment of thin material, either a shadowproof slip which does not support the bust, or a separate brassière and a separate slip. As these garments are bought separately and are probably made by different manufacturers, the shape of each varies. Due to this variation, the neckline contours of the garments vary, two sets of straps that do not align pass over the shoulders and must be held together by fancy clips or clasps and, due to different manufacture of the garments, the large number of seams makes the combination of two garments more bulky and prevents the outer garment from having the smooth contour desirable in women's wear.

The objects of the invention are to provide a combination garment of two portions including a brassière and a slip, that will lend common support to each other; that can be hung on the person from a single pair of shoulder straps, that employ slide fastener or other closing means that function to form the brassière that make it possible to take off and put on the garment readily and quickly; to provide a garment that will supply a brassière and the shadowproofing character necessary; one which can be easily laundered and maintained in a sanitary condition and one which will have a common registering neckline contour.

Another object is to provide a garment as aforesaid in which the slip and brassière are connected together only along the top of the brassière or also at the side seam.

A further object is to provide a garment as aforesaid in which vertically or obliquely disposed fastening means such as zippers are placed in the bottom portion of each cup of the brassière so that the brassière may be loosened when the zippers are opened to facilitate the putting on or removing of the garment.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a front view of a garment constructed in accordance with this invention.

Fig. 2 is a fragmentary view of the inside of the front of the garment.

2

Fig. 3 is a view similar to Fig. 2 with the zippers open.

Fig. 4 is a rear view of the garment.

Fig. 5 is a side view of the garment.

Fig. 6 is an enlarged section on the line 6—6 of Fig. 1.

Fig. 6^a is a section similar to Fig. 6 showing a different method of joining the brassière and slip.

10 Fig. 7 is a fragmentary rear view of a garment constructed in accordance with a modification of this invention.

Fig. 8 is a fragmentary rear view of a garment constructed in accordance with a further modification of this invention.

15 Fig. 9 is a side view of another modification of the invention.

Fig. 10 is a fragmentary sectional view showing the inside of the front of a garment constructed in accordance with the form of the invention shown in Fig. 9.

Fig. 11 is a fragmentary sectional view showing the inside of the front of a garment constructed in accordance with another modification of this invention.

20 The garment shown in Figs. 1-6 comprises a slip 10, an upper part of the slip 10' and a brassière 11. The slip and the brassière are each adapted to perform their own function without 30 interdependence. That is, no part of the brassière forms part of the slip, and no part of the slip aids or forms part of the brassière, except, of course, the usual shoulder straps. In this way, neither the slip nor the brassière gives up 35 any quality in favor of the other.

The slip and the brassière are connected for common support in such a way that no interdependence arises, except through the straps. The slip has the usual straps 12 but these may 40 be eliminated if desired and the support may be obtained from the breasts contained in the brassière. However, at times the brassière will be rendered ineffective, as will presently appear, and at such times straps will be necessary to prevent 45 the garment from falling. Therefore, the garment is preferably provided with straps.

The brassière includes two cups 13 of fabric reinforced by an insert piece 13^a and may be made separately from the fabric of the slip, and 50 may be of different quality, with the slip fabric being lighter and the brassière fabric being heavier or as preferred. The top edges 14 of the brassière are enclosed in a fold 15 of the slip (see Fig. 6), or by joining of the hems as at 15^a (Fig. 6^a), the edge of the slip and brassière being

attached securely and in a manner so that no frayed edge will be exposed. These parts are fastened by stitches 16. The remainder or bottom of the brassière is provided with a firm edge such as is hemmed at 17 and sewed with stitches 18, or may be in some other manner to present a firm edge finish to insure support. The side ends of the brassière are also stitched to the slip at 16^a. While the entire bottom edge of the brassière is free from connection with the slip, a backing or finished edge may be provided, as the bottoms of brassières often have a selvage or elastic border as well as a stitched hem or laced border to provide a firm edge which keeps the brassière in form fitting shape.

Each of the brassière cups 13 has a vertical slit 19 extending from its center through its bottom and a zipper 20 or other form of fastening means may be used to close this slit. When the zipper or fastening means employed is closed, the brassière is in operative position. When the brassière is not needed, the zippers are opened as shown in Fig. 3. The fastening means are also used in putting on and taking off the garment, the fastening means being open at these times.

The brassière is also provided with a back portion 21 which extends from one brassière side-end seam around the back of the wearer to the other brassière side-end seam. This back portion is openable and has tensioning means 22 in its middle. The back portion extends substantially from side seam to side seam of the slip, that is, between the side seams 23 of the slip, and need not open in the tensioning portion as the opening may be placed wherever desired. The garment shown in Fig. 7 distinguishes from the garment of Figs. 1-6 in that the openable meeting ends of a back portion 21 are secured by fasteners 21^b and the back portion is forked at its ends, the branches 24 thus formed extending at the top to the adjacent front sections just below the center of the cup, and at the bottom to the adjacent face front sections of bottom of the brassière. In other respects this garment is identical to the garment of Figs. 1-6 and similar parts are indicated by like references with the letter "a" annexed, and no further description thereof is deemed necessary.

The garment of Fig. 8 distinguishes from the garment of Fig. 1 in that the material of the brassière extends around to the back of the garment and is not attached at the side seams, and the opposing ends 25 thereof are joined by an openable portion having tensioning means therein. Other parts corresponding to like parts of the garment of Fig. 1 are indicated by like references with the letter "b" annexed.

The garments of Figs. 9 and 10 distinguish from the garment of Fig. 1 in that the fastening means 26^c are inclined and diverge downwardly. Other parts corresponding to like parts of the garment of Fig. 8 are indicated by like references with the letter "c" annexed.

The garment of Fig. 11 distinguishes from the garments shown in Figs. 8, 9, and 10 in that hooks 26 hang from the bottom edge of a deeper or wider brassière for attachment to a girdle (not shown) and the zippers 20^d extend to the bottom of the brassière. These long brassières made to hook onto the girdle back and front and to give additional support may be made of lace or sheer material and have elastic and lastex inserts where it may be needed according to the build of the garment. Other parts corresponding to like parts of

the garments of Figs. 8, 9 and 10 are indicated by like references with the letter "d" annexed.

It is obvious that while shoulder straps have been shown that the brassière can, with sufficient tightness, retain the garment about the body of the wearer without the shoulder straps. This is effected through the fastening of the edges of the slits which extend from substantially the center of the cup-shaped portions through the bottom edge of the brassière.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A garment comprising a slip, said slip including a waist covering portion and having a top edge adapted to lie above the breasts, a brassière having two cup-shaped portions for receiving the breasts and disposed inside of said slip, the top edge of the brassière being attached to the top edge of said slip, said brassière having its bottom edge free of any attachment with said slip, each of said cup-shaped portions having a slit extending from substantially the center of the cup-shaped portion through the bottom edge of the brassière, fastening means for securing the edges of said slits together and means for tensioning the brassière about the body of the wearer in tight engagement with the breasts to support the same.

2. A garment comprising a slip, said slip, including a waist covering portion adapted to lie over the breasts and a top edge adapted to surround the wearer above the breasts, a single pair of shoulder straps adapted to extend over the shoulders of the wearer to support the garment, a brassière disposed inside the slip and having a top edge attached to the top edge of the slip consecutively at the front, sides and back thereof and over the points of connection of the shoulder straps therewith, said brassière having its bottom edge free of any attachment with the slip, said brassière having cup-shaped portions, each of said cup-shaped portions of the brassière having a slit extending from substantially the center of the cup shaped portion through the bottom edge of the brassière, means for fastening the edges of the slits together, and means for tensioning the brassière about the body of the wearer to bring the brassière into tight engagement with the breasts to support the same.

3. A garment comprising a slip, said slip including a waist covering portion adapted to lie over the breasts and a top edge adapted to surround the wearer above the breasts, a single pair of shoulder straps adapted to extend over the shoulders of the wearer to support the garment, a brassière disposed inside the slip and having a top edge, said brassière having its top edge attached to the top edge of the slip consecutively at the front and sides and vertically downwardly at the sides to a point intermediate the top and bottom edges of the brassière but leaving the bottom edge thereof free, said brassière having cup-shaped portions, each of said cup-shaped portions of the brassière having a slit extending from substantially the center of the cup-shaped portion through the bottom edge of the brassière,

means for fastening the edges of the slits together, and means for tensioning the brassière about the body of the wearer to bring the brassière into tight engagement with the breasts to support the same whereby the brassière will be tensioned about the wearer from a point just under the center of the cup-shaped portions and therebelow.
